Primary Examiner — Karen E Eldridge Powers*(74) Attorney, Agent, or Firm* — Montgomery Patent & Design, LLC; Robert C. Montgomery; Joseph T. Yaksich**CLAIM**

The ornamental design for a baseball cap front insert, as shown and described.

DESCRIPTION

FIG. 1 is a front perspective view of a baseball cap front insert, showing my new design;
FIG. 2 is a front elevation view thereof;
FIG. 3 is a rear view thereof;
FIG. 4 is a left-side elevation view thereof with a right-side elevation view being a mirror image thereof;
FIG. 5 is a top plan view thereof; and,
FIG. 6 is a bottom plan view thereof.
